UNITED STATES PATENT OFFICE.

GEORGE FREDERICK MOORS, OF OWENSBORO, KENTUCKY, ASSIGNOR TO THE RECIP-
ROTO ENGINE CO., A CORPORATION OF DELAWARE.

ROTARY ENGINE.

1,227,173.

Specification of Letters Patent. Patented May 22, 1917.

Application filed March 19, 1917. Serial No. 155,746.

To all whom it may concern:

Be it known that I, GEORGE FREDERICK MOORS, a citizen of the United States of America, and a resident of Owensboro, in the county of Daviess, State of Kentucky, have invented certain new and useful Improvements in Rotary Engines, of which the following is a full, clear, and exact description, reference being had to the accompanying drawings, forming a part of this specification.

My invention relates to a rotary engine of the type employing a piston eccentrically arranged in a cylinder and an abutment by which movement of fluid in the cylinder is controlled, engines of this type being shown in Letters Patent of the United States Nos. 958,885, 1,029,941 and 1,075,590, issued to me respectively May 24, 1910, June 18, 1912, and October 14, 1913.

The object of the present invention is to provide an improved inlet and exhaust valve construction providing for a reversal of the engine, and to generally improve the engine structure by introducing novel and efficient packing means in combination with the abutment, also an efficient lubricating system, drain features and piston packing features.

Figure I is a side elevation of my rotary engine.

Fig. II is a side elevation, partly in section, one of the cylinder heads being removed.

Fig. III is a view, partly in rear elevation and partly in vertical longitudinal section on line III—III, Fig. I.

Fig. IV is a vertical cross section taken on line IV—IV, Fig. III.

Fig. V is a vertical section taken on line V—V, Fig. III, the reversing sleeve being shown in the position assumed when the engine is reversed.

Fig. VI is a top view of the abutment.

Fig. VII is a side elevation of the abutment.

Fig. VIII is a vertical cross section through the abutment and portions of the cylinder side walls between which the abutment is located.

Fig. IX is a section taken on line IX—IX, Fig. VI.

Fig. X is a longitudinal section through one end of the reversing sleeve surrounding the inlet valve and the lever for operating said sleeve.

Fig. XI is an end elevation, partly in section, of the reversing sleeve and lever.

In the accompanying drawings, A designates a cylinder divided into two compartments by a partition 1, the ends of the cylinder being closed by heads 2. 3 designates a power shaft extending through both compartments in the cylinder A and journaled in said cylinder heads and piston. B are pistons fixed to the power shaft 3 in the cylinder compartments, each piston including an eccentric 4, a peripheral ring 5 and an anti-friction bearing structure between said eccentric and ring.

Each peripheral piston ring 5 is provided with said flanges 6 and 6' which extend toward the axis of the piston and in the outer walls of which are circular grooves 7 and 7', for the reception of packing members about to be described. The walls of said grooves nearest the periphery of the piston are beveled at 8, Fig. III, and in the grooves adjacent to said walls are split packing rings 9 having beveled faces corresponding to the beveled faces 8 against which said packing rings are adapted to bear. Each packing ring 9 is held from circular movement in its pocket by a restraining pin 10 (see Fig. II).

An expanding ring 11 tending slightly toward elliptical shape, is situated immediately within each packing ring 9, and within said ring 11 is a second expanding ring 12 of a shape similar to that of the ring 11. These rings 11 and 12 tending, as stated, toward elliptical shape, or being slightly non-circular, serve to expand the packing ring 9 and therefore adjust the beveled periphery of said packing ring laterally on the beveled face 8 of the groove in the piston ring flange so that said packing ring 9 will be firmly fitted to a wall of a cylinder compartment. The packing ring 9 thus adjusted is designed to prevent the leakage of fluid from the portion of the cylinder compartment around a piston toward the axis of the piston in said compartment. As an additional safeguard to prevent such leakage of fluid I provide each piston ring flange 6, 6' with a second ring 13, which is located in a circular groove 14 nearer the axis of the piston than the previously described rings. These rings 13 are split and are held from turning in the grooves by restraining pins 15. Said rings normally tend to contract and their edges nearest the axis of the

piston are beveled as seen at 13' Fig. III, and are fitted to correspondingly beveled faces at the sides of the grooves 14 nearest the axis of the piston. The normal tendency of the packing rings 13 being to contract, these rings constantly tend to ride laterally in the grooves 14 and press against the adjacent cylinder compartment walls, so that passage of fluid between them and said walls toward the axis of the piston is prevented.

10. In each cylinder is an arcuate abutment 16 carried by an arm 17 pivoted at 18. The arcuate abutment 16 is snugly but movably fitted to the walls of a curved opening in the cylinder, and to prevent the passage of fluid between said walls and the sides of the abutment, I provide the abutment with packing means to be presently described. Each abutment has curved pockets 19 there-

15. in separated by a rounded head member 21, said pockets receiving curved socket members 20 carried by the peripheral rings of the pistons B. The construction just described permits rocking movement of each

20. abutment during the operation of the piston to which the abutment is connected by the socket members 20 and head 21.

25. The means for packing the abutments will now be described. At each end of each abutment is a flanged pocket member 22 having its open side presented toward the opposing wall of the opening in which the abutment operates. Blocks 23 of soft packing are mounted in the pocket members 22,

30. (Figs. II and VIII). These packing blocks are compressed by compressor plates 24 resting on the upper edges of the packing blocks, a presser bar 25 having its ends in engagement with the compressor plates and

35. a draw screw 26 extending centrally through the presser bar 25 into the abutment 16. Between the packing blocks 23 and the rear walls of the pocket members 22 are wedges 27 and 28 reversely positioned relative to

40. each other. The wedges 28 are in contact with the packing blocks 23 and the wedges 27 are located between the wedges 28 and the rear walls of the pocket members 22, between which parts said wedges 27 are

45. movable by adjusting screws 29 in the presser bar 25. It will be understood from the foregoing that the reversely positioned wedges 27 and 28 serve as backing for the packing members 23; also that, by adjusting the draw screw 26, the presser bar 25

50. may be moved inwardly and exert pressure against the compressor plates 24 with the result of squeezing the packing blocks to effect fluid tight joints between such packing blocks and adjacent walls of the opening in which the abutment 16 operates. Should additional adjustment of the packing members toward the cylinder walls be necessary to effect fluid tight joints, such

55. adjustment is readily obtained by adjusting

the screws 29 to shift the wedges 27. From the foregoing description it will be understood that when fluid is delivered into the cylinders of my engine, it is confined in the cylinder chamber and cannot pass between the pistons and the cylinder walls or between the abutments and the walls of the openings in which the abutments are operable. Consequently, the fluid must exert pressure against the eccentrically arranged pistons so that they will operate as described in my earlier patents hereinbefore mentioned.

At the top of the cylinder A is a valve housing 30 having inlet and exhaust pipe connections 31, 32 to which fluid supply and exhaust pipes are attached. The inlet and exhaust pipe connections are located at the longitudinal center of the valve housing 30 and are adapted to be placed in communication with inlet and exhaust ducts 33 and 34 leading to the cylinder compartments of the engine at opposite sides of the abutment 16, one pair of these ducts being shown in full lines Figs. III and IV and 90 in dotted lines Fig. II.

Within the valve housing 30 is a rotatable reversing sleeve 35 containing a longitudinal bore 36 in which valves to be described are operable to control the delivery of fluid to the two cylinder compartments. The reversing sleeve is provided at its longitudinal center with a transversely elongated port 37 communicable with the inlet 31 in the valve housing 30, and contains 100 ports 37, offset from its longitudinal center, adapted to be placed in communication at different times with the inlet and exhaust ducts 33 and 34 leading to and from the cylinder compartments, there being two 105 pairs of the ports 37, one for registry with the ducts leading to one of the cylinder compartments and the other for registry with the ducts leading to the other cylinder compartment. The reversing sleeve 35 contains arcuate transverse channels 35' open to communication with an exhaust chamber 34' extending longitudinally in the valve housing 30. In the bore 36 of the reversing sleeve 35 are independently rotatable semi-cylindrical valves 38. These valves are arranged end to end, one valve controlling the passage of fluid to one cylinder compartment and the other valve controlling passage of fluid to the other cylinder compartment of the engine. Each of the valves 38 is provided with a plurality of ports 39 (see Figs. II, III and IV). The valves are duplicates of each other, but are offset in positions so that fluid will pass through only one of them at a time to a cylinder compartment to supply motive force for the operation of the piston therein. It is well to here state that the two valves 38 are alike and operate alike, but alternately, each valve 110

115. 120. 125. 130.

being set opposite to the other so that when one is receiving operating fluid and delivering it to one of the cylinder compartments, the other valve prevents the delivery of fluid to the second cylinder compartment, and the fluid in the second compartment operates against the piston therein by expansion only except for the lap or lead which exists between the direct flow against the 10 pistons.

One of the valves 38 is secured to an operating rod 40 on which the second valve is loosely mounted, and the second valve is secured to a sleeve 41 also loosely fitted to 15 said rod. The means for rocking the valves 38 in the reversing sleeve comprises an eccentric 42 (see Fig. I) secured to the power shaft 3 an eccentric strap 43 surrounding said eccentric, and connecting rods 44, 44' 20 leading from said eccentric strap to cranks 45 and 46 secured in offset positions to the rod and sleeve 41.

The reversing sleeve 35 has fitted to it at suitable locations packing rings 35^a (see 25 Figs. III and X) which prevent leakage of fluid longitudinally of the sleeve from the intended channels between it and the inner wall of the valve housing 30 in which said sleeve is located.

30 At one end of the valve housing 30 is a horizontal bracket 47 which serves as a bearing for a stem 48 by which the reversing sleeve is rotated. The stem 48 extends through a packing box 50 (see Fig. X) and 35 is provided at its inner end with a head 49 which fits in a transverse slot at an end of the reversing sleeve. 51 is an operating lever fixed to the stem 48. This operating lever is located in juxtaposition to a sector 40 52 supported by the bracket 47, the said sector being provided with notches 53 adapted to receive a latch bolt 54 carried by the operating lever and under the control of a push rod 55 extending longitudinally of said 45 operating lever.

When the pistons, the reversing sleeves 35 and the valves 38 of my engine are in the position shown in the drawings, steam or other fluid used for motive power, on entering 50 through the inlet pipe connection 31, passes through the transversely elongated port 37 at the longitudinal center of the reversing sleeve 35 into both of the semi-cylindrical valves 38. Only one of said valves at this time is adjusted, as seen in 55 Figs. II and V, to permit passage of fluid therethrough as indicated by the arrows and the fluid passes through the valve into the inlet duct 33 beneath said valve and 60 through said duct to the corresponding cylinder chamber, as indicated in Fig. II. The fluid enters the cylinder chamber at the left hand side of the arcuate abutment 16, and its connection to the eccentrically 65 mounted piston B, and exerts pressure

against said piston to turn it in the direction indicated by the arrow on the piston. As the movement of the piston progresses, the fluid in front of it is exhausted into the exhaust duct 34 at y and traverses said duct 70 to the arcuate transverse channel 35' in the reversing sleeve 35 through which it passes into the exhaust chamber 34' to find escape into the exhaust pipe leading from the engine.

75 From the foregoing description, it will be apparent that the valve 38 through which fluid has passed to a cylinder chamber is moved into position to permit said passage through the medium of the eccentric 42, eccentric strap 43, and the operating connections between said eccentric strap and the valve. It will be further understood that the other valve 38 has at this time been so adjusted by the same eccentric as to prevent 80 passage of fluid therethrough to the inlet port 33 controlled thereby. When the piston B in the cylinder to which fluid is first admitted, as described, has partaken of a certain degree of movement, the second 85 valve becomes adjusted to a position corresponding to that of the first valve, and fluid then passes through the second valve, the inlet port 33 with which it is communicable and into the second cylinder compartment to 90 press against the eccentrically mounted piston therein, which has at this time become adjusted to the position assumed by the first piston when it is ready to receive fluid delivered through the first mentioned inlet 95 duct 33.

The foregoing description applies to the 100 positions of the parts of my engine when the engine is running in a forward direction, and at which time the operating lever 51 occupies the position shown in Fig. II, and 105 is held in such position by the engagement of the locking bolt 54 in one of the notches 53 in the sector 52. To reverse the engine, the operating lever 51 is shifted to carry the 110 locking bolt 54 to the second notch 53. In so moving said operating lever the reversing sleeve 35 is partially rotated with a result of placing ports 37 in registration with the exhaust ducts 34, and placing the arcuate 115 channels 35' in the reversing sleeve in communication with the inlet ducts 33. When this adjustment of the reversing sleeve has been made the exhaust ducts 34 become inlet ducts and the inlet ducts 33 become exhaust 120 ducts. The fluid then entering the valves 38 passes through ports 39 in said valves, ports 37' in the reversing sleeve to the ducts 34 and therethrough to the cylinder compartments, entering the latter at the right hand 125 sides of the abutments 16 and acts to operate the pistons in the same manner as has already been described, except in a reverse direction.

130 It is possible to stop the operation of my

engine quickly without shutting off the delivery of fluid through the inlet pipe, but by adjustment of the reversing sleeve 35 to a neutral position. Upon moving the operating lever 51 to a position midway between the two notches 53 in the sector 52, as shown in Fig. XI, the reversing sleeve is so positioned that the inflow of fluid will be divided, the fluid passing through the ports 37 in the reversing sleeve to both of the ducts 33 and 34 so that it is delivered into the cylinder chambers at opposite sides of the abutments 16. The pressure at opposite sides of said abutments is, therefore, balanced and the exhaust from each cylinder chamber is shut off, hence the pistons are quickly brought to rest.

Lubricant is supplied to the pistons of my engine through a check valve 56 (see Figs. I and II) in communication with a duct 57 leading longitudinally in the wall of the cylinder A to the ends of the cylinder. The duct 57 communicates with ducts 58 in the cylinder heads 2 leading in said cylinder heads to the interior of the bearing cases 2^a around the power shaft 3. The lubricant delivered into the chamber of said bearing case acts to lubricate the bearings therein and flows from such chamber through outlet tubes 59 into grooves 60 in spacing rings 61 secured to the eccentrics 4 of the pistons B. The outer walls of said spacing rings contain circular slots into which the tubes 59 extend and which permit of the spacing rings operating around said tubes. From the grooves in the spacing rings 61 the lubricant passes through tubes 62 into ducts 63 in the piston eccentrics 4 and the inner members of the anti-friction bearings between the piston eccentrics and the peripheral rings of the piston. Lubricant is, thereby, constantly delivered to the anti-friction bearings just mentioned.

To prevent water of condensation from interfering with the operation of the pistons in my invention when steam is used as a motive power, I provide each piston with transverse grooves 64 located in the periphery of the piston (see Fig. II). I also provide a cylinder compartment drain 65 which communicates with a discharge pipe 66 through which water of condensation may be withdrawn at intervals, the said pipe being provided with a valve 67 (see Fig. I). Drain ducts 68 lead from each side of each cylinder compartment in the cylinder heads and partition between the compartments. These ducts communicate with an escape pipe 69 (see Fig. III), and any water of condensation accumulating between the packing rings in the sides of the piston is vented through said ducts and pipe.

In each compartment of the cylinder A of my engine is a Babbitt or anti-friction lining a (see Figs. II and III) which is

interlocked with the annular wall of the cylinder, as shown. This lining is non-corrodible, may be readily applied to conform to the pistons operable in the cylinders, so that the contact between the periphery of the pistons and the face surrounding them is greatly improved. Furthermore, scale or other hard substance entering the cylinder becomes embedded in the soft lining, and the liability of damage to the pistons and the wall of the cylinder by such hard substances is eliminated.

I desire to mention that the lever 51, by which the reversing sleeves 35 are operated, may be located at either end of the valve housing 30, in which event the cranks 45 and 46 and the parts associated therewith, will be located at the opposite end, these parts being interchangeable with each other. The outer end of each reversing sleeve is provided with a transverse slot to receive the T-head 49 of the stem 48 to which the operating lever 51 is secured, and the valve housing head in which said stem is mounted may be interchanged with the head at the opposite end of the valve housing, and when such interchange is made the T-head 49 is received by the slot in the adjacent reversing sleeve.

It will, of course, be understood that when the parts are interchanged as mentioned, it is necessary to locate the eccentric 42 and parts coöperable therewith at the end of the engine at which the cranks 45 and 46 are located.

I claim:

1. In a rotary engine, a cylinder, a piston in said cylinder, an abutment connected to said piston and adapted to partake of movement in response to movement of said piston, compressible packing members carried by said abutment, means for compressing said packing members, and means for adjusting said packing members toward the walls of the cylinder in which said abutment operates.

2. In a rotary engine, a cylinder, a piston operable in said cylinder, an abutment connected to said piston and movable in response to movement of the piston, pockets at the ends of said abutment, packing members in said pockets, and means for compressing said packing members in said pockets to effect fluid tight joints between the ends of the abutment and the opposing cylinder walls.

3. In a rotary engine, a cylinder, a piston operable in said cylinder, an abutment connected to said piston, pockets at the ends of said abutment, packing blocks in said pockets, compressor plates resting on said packing blocks, and a presser bar connected to said abutment and arranged in engagement with said compressor plates.

4. In a rotary engine, a cylinder, a piston

in said cylinder, an abutment connected to said piston, packing blocks at the ends of said abutment, wedges for adjusting said packing blocks toward walls of the cylinder between which the abutment operates, and means for adjusting said wedges.

5. In a rotary engine, a cylinder, a piston operable in said cylinder, an abutment in said cylinder connected to said piston, packing blocks at the ends of said abutment, a pair of wedges oppositely disposed relative to each other back of the packing block at each end of said abutment, and means for adjusting one of each pair of said wedges to move the adjacent packing block toward a wall of the cylinder adjacent to the abutment.

6. In a rotary engine, a cylinder, a piston operable in said cylinder, an abutment in said cylinder connected to said piston, pockets at the ends of said abutment, packing blocks in said pockets, a pair of oppositely disposed wedges in each pocket, a presser bar by which pressure may be exerted to compress said packing blocks, and means carried by said presser bar for adjusting one wedge of each of said pairs of wedges to move said packing blocks toward walls of the cylinder.

7. In a rotary engine, a cylinder, a piston operable in said cylinder, said piston having circular grooves in its side faces, the walls of said grooves nearest the periphery of the piston being beveled, an expansible packing ring in each groove having a beveled face contacting with the beveled face of said groove, and means for expanding said packing ring to cause it to ride laterally on the beveled wall of said groove.

8. In a rotary engine, a cylinder, a piston operable in said cylinder, said piston having circular grooves in its side faces, the walls of said grooves nearest the periphery of the piston being beveled, an expansible packing ring in each groove having a beveled face contacting with the beveled face of said groove, an expanding ring arranged within said expansible packing ring whereby the latter is expanded and caused to ride laterally along the beveled wall of said groove.

9. In a rotary engine, a cylinder, a piston operable in said cylinder, said piston having circular grooves in its side faces, the walls of said grooves nearest the periphery of the piston being beveled, an expansible packing ring in each groove having a beveled face contacting with the beveled face of said groove, and a non-circular expanding ring located within said expansible packing ring whereby the expansible ring is caused to ride laterally along said beveled wall of the groove in which the rings are seated.

10. In a rotary engine, a cylinder, a pis-

ton operable in said cylinder, said piston having circular grooves in its side faces, the walls of said grooves nearest the periphery of the piston being beveled, an expansible packing ring in each groove having a beveled face contacting with the beveled face of said groove, and an expansible non-circular expanding ring within said expansible packing ring whereby the latter is caused to move laterally along the beveled wall of said groove.

11. In a rotary engine, a cylinder, a piston operable in said cylinder, said piston having circular grooves in its side faces, the walls of said grooves nearest the periphery of the piston being beveled, an expansible packing ring in each groove having a beveled face contacting with the beveled face of said groove, and a pair of non-circular expanding rings located one within the other in said groove, the outermost of said expanding rings being arranged in contact with said packing ring to expand it and cause it to move laterally along the wall of said groove.

12. In a rotary engine, a cylinder, a piston in said cylinder having a pair of grooves in one of its side faces, each groove having a beveled wall, an expansible packing ring in one of said grooves movable laterally along its beveled wall, means for expanding said packing ring, and a contractible packing ring in the other groove movable laterally along its beveled wall.

13. In a rotary engine, a cylinder having two compartments, a piston in each of said compartments, abutments in said cylinder connected to said pistons, a valve housing having ducts therein in communication with said cylinder compartments at opposite sides of the abutments, a ported reversing sleeve in said valve housing, and a pair of valves in said reversing sleeve for controlling the flow of fluid to and from said cylinder compartments.

14. In a rotary engine, a cylinder having two compartments, a piston in each of said compartments, abutments in said cylinder connected to said pistons, a valve housing having ducts therein in communication with said cylinder compartments at opposite sides of the abutments, a ported reversing sleeve in said valve housing, and a pair of valves in said reversing sleeve for controlling the flow of fluid to and from said cylinder compartments, said reversing sleeve having ports through which fluid may be delivered from said valves to each of the cylinder compartments at either side of the abutment therein.

15. In a rotary engine, a cylinder having two compartments, a piston in each of said compartments, abutments in said cylinder connected to said pistons, a valve housing having ducts therein in communication with

said cylinder compartments at opposite sides of the abutments, a ported reversing sleeve in said valve housing, and a pair of valves in said reversing sleeve for controlling the flow of fluid to and from said cylinder compartments, said reversing sleeve having an inlet port and ports through which fluid may be delivered to each of the cylinder compartments at either side of the abutment therein.

16. In a rotary engine, a cylinder having two compartments, a piston in each of said compartments, abutments connected to said pistons, a valve housing having ducts therein leading to opposite sides of said abutments, a reversing sleeve in said valve housing having an inlet port and ports for communication with either of the ducts leading to each compartment, a pair of ported valves movable independently of each other in said reversing sleeve for controlling the delivery of fluid to said cylinder compartments, and means for operating said valves.

17. In a rotary engine, a cylinder having two compartments, a piston in each of said compartments, abutments connected to said pistons, a valve housing having ducts therein leading to opposite sides of said abutments, a reversing sleeve in said valve housing having an inlet port and ports for communication with either of the ducts leading to each compartment, a pair of ported valves arranged end to end in said reversing sleeve having communication with the inlet port in said reversing sleeve in common and having ports through which fluid may be delivered successively first to one of the cylinder compartments and then the other compartment, and means for operating said valves.

18. In a rotary engine, a cylinder, a pis-

ton within said cylinder, comprising an inner member, an outer member, and an anti-friction device between said members, said piston being provided with a lubricant passageway leading therethrough to said anti-friction bearing device, and said cylinder being provided with a lubricant passageway through which lubricant is delivered to the passageway in said piston.

45

19. In a rotary engine, a cylinder having a lubricant passageway leading through its wall and having a well in which the lubricant delivered through said passageway may collect, and a piston in said cylinder having a lubricant passageway therein in communication with said well.

50

20. In a rotary engine, a cylinder having a lubricant passageway leading through its wall and having a well in which the lubricant delivered through said passageway may collect, and a piston in said cylinder having a lubricant passageway therein in communication with said well, said piston being provided with a grooved spacing ring communicating with the passageway in the piston, and said cylinder having mounted therein a conducting tube extending into said spacing ring through which lubricant may pass from said well to said spacing ring and be delivered into the passageway in said piston.

60

21. In a rotary engine, a cylinder having a piston compartment, a piston in said compartment, and packing rings in the sides of said piston, said cylinder being provided with drain ducts leading from the sides of said piston through which water of condensation may be withdrawn.

65

In testimony that I claim the foregoing I hereunto affix my signature.

GEORGE FREDERICK MOORS.
